United States Patent Office.

JOHN DANNER, OF CANTON, OHIO.

Letters Patent No. 78,931, dated June 16, 1868.

IMPROVEMENT IN PENCIL-SHEATH.

The Schedule referred to in these Letters Patent and making part of the same.

TO ALL WHOM IT MAY CONCERN:

Be it known that I, JOHN DANNER, of Canton, in the county of Stark, and State of Ohio, have invented certain new and useful Improvements in a Pencil-Point Protector and Pencil-Holder; and I do hereby declare the following to be a full, clear, and exact description of the same, reference being had to the accompanying drawings, making a part of this specification, in which—

Figure 1 represents the article in question, with a pencil placed therein.

Figure 2 represents a vertical section through the same, and

Figure 3 represents the rubber holder for protecting the point of the pencil.

Similar letters of reference where they occur in the separate figures denote like parts in all of the drawings.

My invention consists, first, in a pencil-case or socket, having a rubber or other elastic lining in the interior thereof, for protecting the point, and holding the pencil to or in the case.

To enable others skilled in the art to make and use my invention, I will proceed to describe the same with reference to the drawings.

a represents a metallic case, made of thin sheet metal of any kind, the portion *b* of which is made larger than the body *a*, and enough larger to receive and hold an India-rubber or other elastic lining, *c*, which, for cheapness and efficiency, may be simply a piece of India-rubber tubing, as shown in fig. 3.

The tube or case *a* is made to receive any ordinary-sized lead-pencil, *d*, and when the lining is inserted, its bore or central opening should be slightly less than the diameter of the pencil, so that it will embrace it with friction enough to hold the pencil.

The point *e* of the pencil does not extend to the bottom of the case, but is protected by the lining *c*, and if at any time the point of the pencil should descend so far as to come in contact with the bottom of the case, which is ordinarily of metal, a cushion or pad of some soft material may be placed in the bottom, or the lower end of the rubber tube, if that be used, may be closed, or made in a cup-form, for the purpose.

The enlarged chamber *b* at the bottom of the case is important, not only to hold the lining, and prevent it from being drawn out, but also to allow the lining to expand when the pencil is pushed into it. The chamber *b* need not necessarily be at the bottom of the case, nor is it actually necessary that the bottom of the case should be closed, but it is convenient to make them in this way.

The case *a* may be a-tube, and the enlarged portion *b* at or near the centre of it, so that the pencil would be held higher up, whilst the point could not be forced against anything hard enough to break it off.

That the case, and pencil too, when in it, may not be lost or drop out of the pocket, I attach to it a fastening, by which it may be united to the clothes. In the drawings, I have shown a hinged pin, *f*, for this purpose, the point of which, after it has been passed through the clothing, is sprung into an open eye, *g*, in the usual, well-known way. A button, hook, clasp, eyelet, or any other well-known fastening-device, may be used instead of the pin and eye, and the case may be fastened thus in the pocket, or to the outside of the clothing, whichever may be preferred, or two pins may be used on the tube, one projecting downward and the other upward, and may be slightly serrated or roughened, so as to hold better in the cloth. By placing the case in the pocket or moving it downward, one pin would take in the fabric, and then, by slightly raising it, the other would take also in the fabric, and the two thus firmly hold the case. This kind of fastening would require no difficult manipulation.

Having thus fully described my invention, what I claim therein as new, and desire to secure by Letters Patent, is—

A pencil-case or socket, with a rubber or other flexible or elastic lining, *c*, contained in an enlarged chamber, *b*, in the inside thereof, which rubber will, by its friction, hold a pencil inserted therein, and protect its point, and be itself held in the chamber by the recessed shoulders thereof, substantially as described.

JOHN DANNER.
